I. H. SCLATER

TRANSFORMER

Filed Nov. 18, 1926

Inventor:
Ivanhoe H. Sclater,
by *Ivanhoe H. Sclater*,
His Attorney.

UNITED STATES PATENT OFFICE.

IVANHOE H. SCLATER, OF PITTSFIELD, MASSACHUSETTS, ASSIGNOR TO GENERAL ELECTRIC COMPANY, A CORPORATION OF NEW YORK.

TRANSFORMER.

Application filed November 18, 1926. Serial No. 149,238.

My invention relates to transformers and more particularly to transformers of the shell type in which the core comprises a central leg surrounded by the windings and a plurality of outside legs joined by suitable core yokes to the central leg to provide return paths for the magnetic flux induced in the central or winding leg. The general object of the invention is to provide an improved arrangement of windings whereby the transformer may have low reactance and the high voltage winding be well ventilated and insulated and easily accessible for the attachment of any desired connections such as the main high voltage leads and tap connections such as the main high voltage leads and tap connections.

The invention will be better understood from the following description taken in connection with the accompanying drawing in which Fig. 1 is a cross sectional view of a transformer constructed in accordance with the invention, the section being taken on the line 1-1 of Fig. 2, and Fig. 2 is a vertical sectional view of one side of the transformer taken on the line 2-2 of Fig. 1.

Like reference characters indicate similar parts in both views of the drawing.

The transformer which is shown in the drawing to illustrate the invention comprises a magnetic core having a center leg 10 and a plurality of outer legs 11, four in number in the present instance, the center and outer legs being connected by yokes 12 to provide return paths for the magnetic flux induced in the center leg. The low and high voltage windings surround the center core leg 10, the low voltage winding being formed in two spaced concentric sections 13 and 14 which may be connected in series and the high voltage winding 15 comprising a stack of disk coils located concentrically between the two sections of the low voltage winding. With this arrangement of the windings, the high voltage winding is well surrounded by the low voltage winding so that the reactance of the transformer will be low.

The inner section 13 of the low voltage winding and the high voltage winding are supported radially by the center core leg 10 and are preferably separated from each other by spacers 16 to provide a ventilating duct. The outer section 14 of the low voltage winding is spaced from the high volt-

age winding 15 and is supported radially entirely by the surrounding outer legs 11 of the core, suitable blocks or spacers 17 being interposed if desired.

The individual disk coils of the high voltage winding 15 are spaced and insulated from each other by annular layers or collars 18 of insulating material, the outer edge portions of these insulating collars extending beyond the outer faces of the coils and into the surrounding space to increase the breakdown leakage paths between adjacent coils. The absence of any inside radial supports for the outer section 14 of the low voltage winding permits the insulating collars 18 to extend uniformly and with uninterrupted edge portions all around into the space surrounding the high voltage winding. This space may also be used to accommodate the main leads and any desired tap connections from the high voltage winding.

It will be obvious that modifications of the specific construction which has been described may be made without departing from the invention as defined in the appended claims.

What I claim as new and desire to secure by Letters Patent of the United States, is:—

1. A transformer including a magnetic core comprising a center leg and a plurality of outer legs surrounding said center leg, a high voltage winding, a low voltage winding formed in two sections, the high voltage winding being concentrically arranged between said two low voltage winding sections, one of said low voltage winding sections and the high voltage winding surrounding said center core leg and being supported radially thereby, the other of said low voltage winding sections surrounding and being spaced from said high voltage winding, said latter low voltage winding section being supported radially entirely by said outer core legs, said high voltage winding comprising a stack of disk coils, and a plurality of annular insulating collars separating said disk coils and extending beyond the outer surface of said high voltage winding into the space between said high voltage winding and said outer low voltage winding section.

2. A transformer including a magnetic core comprising a center leg and a plurality of outer portions providing return paths for the magnetic flux, each of said outer portions comprising an outer core leg and two

yokes connecting its ends to the ends of said center leg, a high voltage winding, a low voltage winding formed in two sections, the high voltage winding being concentrically arranged between said two low voltage winding sections, one of said low voltage winding sections and the high voltage winding being supported around said center core leg, the other of said low voltage winding sections surrounding and being spaced from said high voltage winding, said latter low voltage winding section being supported entirely by said outer core portions, said high voltage winding comprising a stack of disk coils, and a plurality of annular insulating collars separating said disk coils and extending beyond the outer surface of said high voltage winding into the space between said high voltage winding and said outer low voltage winding section. 15
 In witness whereof, I have hereunto set my hand. 20

IVANHOE H. SCLATER.

Certificate of Correction.

Patent No. 1,652,911.

Granted December 13, 1927, to

IVANHOE H. SCLATER.

It is hereby certified that error appears in the printed specification of the above-numbered patent requiring correction as follows: Page 1, lines 16 and 17, strike out the words "such as the main high voltage leads and tap connections"; page 2, line 9, claim 2, for the syllable "wind-" read *winding*; and that the said Letters Patent should be read with these corrections therein that the same may conform to the record of the case in the Patent Office.

Signed and sealed this 17th day of January, A. D. 1928.

[SEAL]

M. J. MOORE,
Acting Commissioner of Patents.
